United States Patent Office

Des. 224,179
Patented July 4, 1972

224,179

SHELLER FOR PEAS OR THE LIKE

George F. Taylor, P.O. Box 625, Moultrie, Ga. 31768

Filed Nov. 23, 1970, Ser. No. 26,113

Term of patent 14 years

Int. Cl. D7—04

U.S. Cl. D89—1

FIG. 4

FIG. 3

FIG. 1 is a perspective view of a sheller for peas or the like showing my new design;

FIG. 2 is a right side elevational view;

FIG. 3 is a front elevational view; and

FIG. 4 is a left side elevational view.

I claim:

The ornamental design for a sheller for peas or the like, substantially as shown.
